UNITED STATES PATENT OFFICE.

JAMES A. WISE AND BENJAMIN J. TARBUTTON, OF SANDERSVILLE, GEORGIA.

AIR MOISTENER FOR INTERNAL-COMBUSTION ENGINES.

Application filed July 23, 1924. Serial No. 727,799.

To all whom it may concern:

Be it known that we, JAMES A. WISE and BENJAMIN J. TARBUTTON, citizens of the United States, residing at Sandersville, in the county of Washington and State of Georgia, have invented certain new and useful Improvements in Air Moisteners for Internal-Combustion Engines; and we do hereby declare the following to be a full, clear, and exact description of the invention, such as will enable others skilled in the art to which it appertains to make and use the same.

This invention relates to air moistening devices for internal combustion engines and has for its object to provide a device of this character which will be simple in construction and inexpensive to manufacture.

With these and other objects in view, the invention resides in the novel combinations of parts more fully hereinafter disclosed and particularly pointed out in the claims.

Referring to the drawings, in which like numerals designate like parts in all the views, and which are to be taken as a part of this specification,

Figure 1 is a front elevational view of the device shown associated with the dial board of an automobile;

Figure 2 is a side elevational view partly in section of the parts shown in Fig. 1;

Figure 3 is a rear view of the device.

Figure 4 is a transverse fragmentary sectional view taken on the line 4—4 of Fig. 1; and

Figure 5 is a fragmentary sectional view taken on the line 5—5 of Fig. 1.

This device comprises a cylindrical casing 1 provided with the rear wall 2, which is of such a thickness as to contain the cylindrical bore 3, forming a passageway for the water. The front of the casing 1 is provided with the vision glass 4, held in place as by the spring ring 5 and forming a leak-proof joint to prevent the escapement of any water that might collect within said casing. Near the upper end of the passageway 3, as seen in Fig. 2, there is provided an outlet nozzle or passageway 6 which is inclined downwardly as shown, to insure the drip of the water from the passageway 3.

The casing 1 is suitably supported on the dial board 10 of an automobile and in direct view of the driver of said automobile. Rigid with the casing 1 and forming a valve housing associated therewith is the lug 11 pro-

vided with a bore 12 through which is adapted to pass and operate a needle valve 13 operated as by the thumb nut 14 on the front side of the dial plate 10. The needle valve is suitably mounted in the packing joint 15, as clearly indicated in the views.

The lower end of the passageway 3 connects with the transversely positioned bore 12 located in the lug 11, as clearly shown in Fig. 5. Leading from the rear end of the lug 11 is the water supply tube 20, adapted to connect with the water circulatory system, but said connection is not shown in the drawings. The inner end of the water pipe 20, see Fig. 5, is positioned within the bore 12 of the lug 11 and its end is suitably ground so as to form the valve seat 21 to take the end of the adjustable needle valve 13. Thus, water from the circulatory system may pass through the pipe 20, past the needle valve 13, into the bore 12 and thence upwardly through the passageway 3 and drip from the outlet 6 into the interior of the cylindrical casing 1.

Near the lug 11 is fastened to the casing 1 an L-shaped casting 25, see Figs. 3 and 4. This casting is provided with the passageway 26, the lower end of which terminates in the enlarged end 27 which is suitably bored to receive one end of the air supply pipe 28 which, preferably, extends well under the hood 18 of the engine so that the warm air surrounding the engine is drawn through said tube 28. Air coming through the pipe 28 will pass in the direction of the arrows, upwardly through the passageway 26, into the bore 29 adapted to house the air supply needle valve 30 tapered at its extreme end as shown and operated by the thumb nut 31. The rear end of the bore 29 is adapted to receive one end of the discharge pipe 35 which serves to conduct away from the casing 1 the air after it has been moistened by the water, and deliver the same to the intake manifold (not shown) of the engine. The inner end of the pipe 35 is suitably ground to form the valve seat 36 for the end of the adjustable needle valve 30, said needle valve 30 being mounted in a suitable packing joint 15.

Connecting the interior of the casing 1 with the pipe 35 is an outlet passageway 40 inclined to said discharge pipe 35 as shown and through which the water from the said casing may pass, as well as air from the bore 29. It will be observed that in mount-

ing the casing 1 on the dial plate 10, see Fig. 1, the outlet passageway 6 is placed at the uppermost position of said casing, and lying in a vertical plane which is equidistant, approximately, from the two needle valves controlling the water and air inlets. This, due to the fact that the said casing 1 is cylindrical in form, provides a pocket or reservoir at the bottom of the casing 1, as indicated at 45, so that at all times there may be present in the casing 1 a small quantity of liquid.

The operation of the device may be understood from the foregoing but will be briefly summarized as follows: Should the conditions be such that it would be advantageous to add moisture to the vapor being drawn into the engine through the intake manifold thereof, the operator of the automobile would turn the water needle valve 13 so as to allow water from the circulatory cooling system to enter by way of the pipe 20, passageway 3 and outlet 6, into the casing 1. He would then open the air needle valve 30 so that there would be created a suction of air through the pipe 28, passageway 26 and pipe 35, to the intake manifold of the engine, due to the partial vacuum created in the pipe 35. This suction in the pipe 35 would be sufficient to draw water from the interior of the casing 1, through the passageway 40, into said pipe, where it would mix with the air forming a fine mist which, when mixing with the gasoline vapor, would make the desirable explosive charge in the engine. The use of such a device as above described would, of course, not have to be used at all times, but would vary with the weather conditions, that is dry or damp weather conditions, and also day or night driving. Also, the use of such a device will cause a better explosion and will combat the formation of carbon in the

cylinders of the engine, thereby saving fuel. It will be observed that due to the tapered end of the valve 30 and the inclination of the passage outlet 40, any air passing said valve 30 will exert a greater or less suction on said outlet 40, and thus tend to draw vapor out of the chamber 1. It will also be observed that by locating the outlet 40 to one side of the vertical plane passing through the nozzle 6, a small quantity of water is always maintained in the chamber 1 to furnish the moisture for the air sucked out of said chamber.

It is obvious that those skilled in the art may vary the details of construction as well as the arrangement of parts without departing from the spirit of the invention, and therefore it is not desired to be limited to the foregoing disclosure except as may be required by the claims.

What is claimed is:

In a device of the character described, the combination of a vertically disposed chamber; an inlet to said chamber comprising a passageway located in the vertical rear wall of said chamber, one end of said passageway terminating in an angularly disposed outlet into said chamber overhanging said wall and located at the top portion thereof, a water supply for said chamber connecting with the other end of said passageway; a valve controlling said water supply; an outlet from said chamber located at the bottom of said wall and to one side of the vertical plane passing through said water inlet; an air supply communicating with said last named outlet to admit air to mix with the water flowing from said outlet; and a tapered valve controlling said air supply.

In testimony whereof we affix our signatures.

JAMES A. WISE.

BENJAMIN J. TARBUTTON.
